BROKEN LINE MAKING ATTACHMENT FOR DRAFTSMEN'S SCALES

Donald Gordon Jackson, Pasadena, Calif.

Application November 13, 1944, Serial No. 563,135

4 Claims. (Cl. 33—39)

1
My invention relates to the art of making drawings and it is particularly useful in the art of mechanical drafting, although it can be used for other purposes. In making working and other drawings of machinery, tools, and the like it is highly desirable that lines used to define dimensions be made of broken or interrupted lines and is an object of my invention to provide a tool by which said broken or interrupted lines may be produced, each portion of said line and the spaces therebetween being of equal length. Further objects and advantages will be made evident hereinafter.

In the drawing, which shows a preferred form of my invention:

Fig. 1 is an elevation showing how my invention is used;

Fig. 2 is an elevation at right angles to Fig. 1 viewed in the direction of the arrow 2 of Fig. 1;

Fig. 3 is an elevation of my tool viewed in the direction of the arrow 3 of Fig. 1;

Fig. 4 is a view of the cam wheel;

Fig. 5 is plan view of my tool as seen from above;

Fig. 6 is an enlarged cross-sectional view taken in the direction of the arrows 6—6 of Fig. 3; and

Fig. 7 shows one kind of line that may be produced by my tool.

The preferred form of my invention shown in the drawing consists of a carriage 11 preferably formed of a metal or plastic sheet. It may be adapted to be used with a conventional draftsman's scale 12 whose section is an equilateral triangle having grooves 13 in the sides 14 thereof. The carriage is so formed that it extends over the top of the scale and has prongs 15 which project into the grooves 13 and thus restrain the movement of the carriage 11 to a straight line parallel to the ruling edge 17 of the scale 12.

The carriage 11 has a housing 18 carrying a wheel 20 turning on a shaft 21. Between the housing 18 and the scale-engaging portion of the carriage is a flat portion 22 which has an opening 23 therein. This opening may be wedge-shaped with rounded ends, as shown in Fig. 6, and is symmetrical about a line defined by a guide line 24 scribed on the top of the flat portion 22.

The housing 18 is preferably bent over, as shown in Fig. 6, to enclose the wheel 20, the top 25 of the housing 18 forming a convenient rest for the right hand 26 of the user, whose left hand 27 holds the scale 12 in the desired position.

The tool is used in the following manner. The carriage 11 is placed on the scale 12, in the posi-

2
tion shown in Fig. 1 and Fig. 2, with the scribed line 24 on the described locus of the broken line and with the edge 17 parallel to this desired line. The user grasps a marking implement, for example, the pencil 30, in his right hand 26, his left hand 27 holding the scale firmly in position. The user then inserts the pencil 30 in the groove 23, resting his hand 26 on the top 25 of the housing 18 of the carriage 11. The user exerts sufficient downward pressure on the top 25 to hold the wheel 20 in good contact with the surface 31, which may be covered with paper or tracing cloth.

The wheel 20 may have various forms, one such form, shown in Fig. 4, being cylindrical about the axis of the shaft but having four teeth or ridges 32 formed thereon. This wheel produces the line shown in Fig. 8 and by varying the form of the wheel 20 and its teeth 32 lines of different appearance may be drawn.

As the user moves the carriage 11 along the scale 12, holding the wheel 20 in contact with the surface 31, the wheel rotates and the teeth 32 periodically lift the pencil 30 from the surface 31, leaving the spaces 35 seen in the line shown in Fig. 7.

This tool has several uses but it has a special utility for draftsmen making drawings having broken dimension lines. By its use a draftsman can draw very uniform broken lines as fast as he can draw continuous ones. Uniformity in these lines seems to be very important to some people such, for example, as the army and navy, who are quite insistent on uniformity in many things.

The carriage 11 is of relatively thin and therefore flexible material, and it fits rather loosely on the scale. Due to this loose fit and the flexibility of the material, the cam wheel 20 has no difficulty in lifting the point of the pencil from the paper. The purpose of the wedge-shaped opening 23 is to accommodate different sizes of leads.

I claim as my invention:

1. A device for ruling interrupted lines on a surface, comprising: a carriage having an opening through which a marking implement can extend and a rest for a hand holding said implement; a straight edge for guiding said carriage in a straight line; and a cam wheel upon which said carriage is supported on said surface, said cam wheel being so formed that as it rolls over said surface it periodically lifts said writing implement in a direction at a right angle to said

surface, thus interrupting the line being scribed by said marking implement.

2. A device for ruling interrupted lines on a surface, comprising: a carriage having an opening through which a marking implement can extend and a rest for a hand holding said implement; a straight edge for guiding said carriage in a straight line, said carriage extending over said straight edge and contacting the top and two sides thereof so that the carriage can move only in the direction of the ruling edge of said straight edge; and a cam wheel upon which said carriage is supported on said surface, said cam wheel being so formed that as it rolls over said surface it periodically lifts said writing implement in a direction at a right angle to said surface, thus interrupting the line being scribed by said marking implement.

3. A device for ruling interrupted lines on a surface, comprising: a carriage having a wedge-shaped slot through which a marking implement can extend and a rest for a hand holding said implement; a straight edge for guiding said carriage in a straight line; and a cam wheel upon which said carriage is supported on said surface, said cam wheel being so formed that as it rolls over said surface it periodically lifts said writing implement in a direction at a right angle to said surface, thus interrupting the line being scribed by said marking implement.

4. A device for ruling interrupted lines on a

surface, comprising: a carriage having a wedge-shaped slot through which a marking implement can extend and a rest for a hand holding said implement; a straight edge for guiding said carriage in a straight line, said carriage extending over said straight edge and contacting the top and two sides thereof so that the carriage can move only in the direction of the ruling edge of said straight edge; and a cam wheel upon which said carriage is supported on said surface, said cam wheel being so formed that as it rolls over said surface it periodically lifts said writing implement in a direction at a right angle to said surface, thus interrupting the line being scribed by said marking implement.
